U.S. Appl. No. 29/603,469, filed May 10, 2017.
 International Search Report and Written Opinion of PCT/US18/29027 dated Jul. 20, 2018.

Primary Examiner — Cynthia Ramirez*Assistant Examiner* — Gino Colan(74) *Attorney, Agent, or Firm* — Elizabeth A. Peters;
 Barnes & Thornburg LLP(57) **CLAIM**

The ornamental design for an oil filter front relief valve, as shown and described.

DESCRIPTION

FIG. 1 is an upper perspective view of an oil filter front relief valve, showing our new design;

FIG. 2 is a bottom perspective view thereof;

FIG. 3 is a left side view thereof;

FIG. 4 is a right side view thereof;

FIG. 5 is a top plan view thereof; and,

FIG. 6 is a bottom plan view thereof.

The broken lines shown in the drawings are for purposes of illustrating portions of the oil filter front relief valve and form no part of the claimed design.
